BODY LOWERING APPARATUS

Edward Sokolik, New Brighton, Minn.

Continuation of abandoned application Serial No.
73,300, January 29, 1949. This application Au-
gust 21, 1952, Serial No. 305,527

9 Claims. (Cl. 254—157)

1

This application is a continuation of my application for Body Lowering Apparatus filed January 29, 1949, Serial No. 73,300, Division 61, which is abandoned in favor of this application, which relates to improvements in apparatus for lowering fire escapees from burning buildings, or material from buildings under construction or destruction.

The principal object is to provide an apparatus whereby bodies or material of predetermined minimum and maximum weights may be lowered from altitudes under governed predetermined rate of descent.

An important object is to provide an apparatus that is streamlined and compact and presents an attractive appearance when designed for use as a fixture mounted over a window to lower fire escapees.

A further object is to provide an apparatus adapted for high as well as for low altitudes.

Another object is to provide an apparatus that has duplex lowering features coacting alternately.

Still another object is to provide an apparatus that is fire, rot, or damage proof.

Still further object is to provide an apparatus that automatically substantially decelerates acceleration.

A very important object is to provide an apparatus that has three separate coacting means to govern the acceleration of the descending body.

Invention resides in novel combination, arrangement and construction of the elements of the apparatus as hereinafter described and defined in the subjoined claims.

Other objects and advantages of the invention will be apparent as the description progresses.

Fig. 1 is a front elevation of the apparatus as it appears when mounted on top of the window casing in a room.

Fig. 2 is a vertical section, axially extended, with a fragmentary edge elevation of the apparatus showing sectionally the duplex reel, the radial brake disks, twin brake drums and the twin assemblies of governor-brake levers provided with brake shoes.

Fig. 3 is a front elevation of the combined radial brake disk and drum, and the governor-brake levers with their brake shoes in braking action.

Fig. 4 shows a side and front end elevation of the bracket shaft support separated from the base-plate.

Fig. 5 is a plan view on line 5—5 Fig. 3 of one of the governor-brake levers with its pivot, which

2

is provided with a sleeve, and the pivot for the shoe, in the respective fulcrums of the lever.

Fig. 6 is a plan view of one of the brake shoes with the pivot for attaching same to one of the governor-brake levers, in its fulcrum.

In the drawings, wherein for the purpose of illustration, is shown a preferred embodiment of my invention, the numeral 8 designates the bracket frame 8, which carries the mechanism.

10 The frame 8 and mechanism combined present the appearance of a large alarm clock secured to the wall in a small out-of-the-way compass above the casing of a window. A peculiar feature of this apparatus is that its dimensions are radially rather than laterally coextensive, imparting thereto an attractive appearance and the function of nullifying acceleration of a descending body.

Included in the bracket frame 8 is: a wall base-plate 9 which is illustrated as of radial design, provided with a base 10 adapted to rest upon the top casing member of a window and is provided with eyelet means 11 whereby it is secured to the wall against which it lays by screws 12 or the like, 20 and is provided with a radial brake face surrounding the axis thereof; and a stub-shaft support 13 perpendicularly rigidly affixed to the brake face of the plate 9. This stub-shaft comprises a journal portion 14 connected to the brake face, and a free end portion 15, which is illustrated as having opposite flat sides and opposite arced sides 16, connected to said journal portion 14. These arced sides are screw threaded from the ends thereof inwardly for same distance. 25 This free end-portion may be structurally modified so long as a member may be moved to and fro thereupon, but not rotated thereupon.

Included in the mechanism supported by the bracket frame 8 is: a duplex-reel 17 rotatably mounted upon the journal portion 14 of the stub-shaft 13, said duplex reel 17 including a drum-hub portion 18 having radial brake-end flanges 19 and 20, each end-flange having a radial brake face on the outer side thereof, said drum-hub portion 18 having a partitional flange 21 medially disposed on said drum-hub portion 18 and of the same diameter as brake end-flange 19. Brake end-flange 20 has a recess 22 extending semi-annularly in the upper top half of the side of the inner edge thereof and has a diameter slightly exceeding that of the flanges 19 and 21. The end-flange 20 is provided on the outer face thereof of near the edge 23 thereof, with a pair of pivots 24 diametrically opposite each other across the central axis of said end-flange 20. Each pivot 24

is provided with a nut or cotter-pin 0 on the projecting end thereof, and in the other end thereof, as illustrated, with a screw thread engaging the screw threaded bore in the end-flange 20.

The partitional flange 21 divides the drum-hub portion 18 into two narrow duplex hubs 25 and 26, each of which is provided with a strand element 27 and 28 respectively. These strands have one end secured to the respective drum-hub-portions and then wound thereupon in opposed directions. Each of the free ends is provided with an eye terminal 29 and 30 respectively for attaching thereto, a body lowering device (not shown).

Each strand 27 and 28 is wound principally radially cumulatively upon the narrow drum hub-portions 25 and 26 respectively, as distinguished from wide hub-portions adapted for laterally cumulative winding. The object of radially cumulative winding is to automatically decelerate or retard acceleration of a descending body and further to gain the advantage of streamlining, of attractive appearance, easy mounting to the wall, and to afford a narrow radially coextensive reel that lays flat upon the wall to which it is secured. A further advantage of this peculiar reel is that it is adapted for lowering bodies from great altitudes, since a strand element being generally a diametrically small cable strong enough to support a person or the material to be lowered.

A hood 31, preferably of some resonance, is demountably mounted upon the top half-portion of the duplex-reel 17 and has the pendant guard ends 32 which also serve as resonant alarms outcurved from the reel 17, since when the first body is being lowered, the eye terminal 29 or 30 of the idling strand strikes the outcurved hood end 32 as it reels thereunder producing a resonant sound to alarm occupants in adjacent rooms. In mounting the hood 31, the edge 33 thereof, which is beveled, is slid into the recess 22 in the edge 23 of the flange 20, and the other edge 34 is forced down onto the flanges 19 and 21 and held thereupon by the pair of set-screws 35 anchored in the base-plate 9.

A brake-member 36 is slideably, but not rotatably, mounted upon the free end-portion 15 of the stub-shaft 13 and includes a combined brake disk 37 having a radial brake face cooperating with the brake face of the end-flange 20 and a brake drum 38 having a cylindrical brake face. The disk 37 has a hub 39, with two opposite inner flat sides and two opposite inner arced sides adapted to slide, but not to rotate upon said end-portion 15. This hub 39 extends into the brake drum 38 substantially one-half of the width of said drum 38.

Another similar brake member 36a is likewise mounted upon the same portion 15, but without a radial brake face on the disk 37a. This member 36a, however, has the hub 39a projected toward the hub 39 of the brake member 36 to effect the spacing between the two brake members 36 and 36a, and to afford hub bearings of corresponding widths.

This brake member 36a has a numerical scale disposed in the confines of said brake member 36a to designate the points to which the nut 43 may be adjusted to create a braking contact between the brake faces of the end-flanges 19 and 20 and the brake faces of the plate 9 and the disk 37 respectively, of such intensity at which the reel 17 with one of its strands 27 or 28 loaded with a person or object of the specific weight indicated at that particular point, will give way to unreeling itself.

A sleeve link 40 is rotatably mounted upon the hub 39a and has a pair of eye anchor means 41 diametrically opposite each other.

A compression coil spring 42 is mounted upon the end-portion 15 of the stub-shaft 13 crowdingly bearing against the disk 37a effecting braking between the end-flange 19 and base-plate 9, and between the flange 20 and brake-disk 37. It will be noted that since the coil spring 42 can be compressed to about one-half its normal spread, the stub shaft portion 15 is screw threaded on its opposite arcs 16 to the middle of the coil spring 42.

A nut 43 screw threadedly cooperates with the screw threaded portion of the stub-shaft portion 15 and bears against the coil spring 42 to regulate the compression upon the brake-disk 37.

A pair of combination governor-brake levers 44 and 45, is rockably mounted upon the inner portion of the pivots 24 in a manner so that one end-portion of each lever, is approximately seven times as long as the other, and so that each short end-portion 46 of each lever 44 and 45 is adjacent to the long end-portion 47 of each lever. These levers are preferably semi-circularly arcuate and structurally identical, each in the form of a semi-ring having a width preferably exceeding the thickness thereof.

Each of the long end-portions 47 of the levers 44 and 45 is shaped to acquire weight toward the end thereof such weight serving as a centrifugal governor actuating the other end-portion 46 which serves as a brake end-portion. Each long end-portion has a laterally projecting anchor means 49 provided with an eyelet and disposed adjacent each pivot 24 a distance therefrom substantially one-half the length of the short end-portion 46.

Each of the short end-portions 46 is shaped generally to reduce weight toward the end thereof which is provided with a brake-shoe 51, said brake-shoe, as illustrated, has a bearing box 53 centrally on the back thereof adapted to be preferably bifurcatedly and rockably connected by each pivot 48 to the end of each end portion 46, and is adapted frictionally to engage the brake-drum 38. These brake-shoes 51 are not full semi-circles so that the ends of the shoes may not abut when braking.

A pair of spacing washers 54 to off-set the levers 44 and 45 from the end-flange 20, is mounted upon the pivots 24. These washers 54 may be in the form of bosses extended from the pivotal bearing box of each lever.

A pair of coil springs 58 for retracting the governor end-portions 47, is connected to the anchor means 49 thereof and to the eye anchor means of the sleeve-link 40. These springs 58 are provided with screw-threaded means which extend through the eyelets in the anchor means 49 and which are provided with nuts 7 for adjusting the retraction tension of the springs 58.

A pair of spacing sleeve washers 52 is mounted upon the pivots 24 adjoining the outer sides of the levers 44 and 45 to afford spaces for the springs 50.

Another pair of governor-brake levers 44a and 45a identical to the levers 44 and 45 and provided with another pair of brake-shoes 51a identical to brake-shoes 51 is mounted upon the pivots 24 adjoining the sleeve washers 52. The only difference between these two pairs of governor-brake levers is that the pair 44a and 45a is mounted functionally to oppose the other pair; thus the long governor end-portions 47 of the pair of levers 75 44 and 45 are disposed opposite and opposed to

the long end-portions of the other pair of governor-brake levers 44a and 45a, consequently while the anchor means 49a are also on the outer side of the levers 44a and 45a, they are, however, on the other side thereof. One pair of governor-brake levers functions when the duplex-reel 17 reels clockwise, and the other pair is idling and vice versa when the duplex-reel reels counterclockwise. When the governor end-portions of one pair governor-brake levers are trailed behind the pivots 24, they function centrifugally actuating the brake end-portions centripetally causing the brake-shoes to brake. The governor end-portions of the other pair of governor-brake levers at the same time are shoved ahead of the pivots 24 retracted by the retraction coil springs and idling together with its corresponding strand.

Another sleeve link 40a with anchor means 41a is rotatably mounted upon the extreme end-portion of the screw threaded portion 15 of the stub shaft 13.

Another pair of coil springs 50a identical to coil springs 50 for retracting the governor end-portions 47a is similarly connected to the anchor means 49a and 41a of the sleeve-link 40a.

The structure of the governor-brake assemblies is the same for all altitudes, but the radial dimension of the reel 17 increases for every story of building altitude.

For lowering fire escapees, a body carrying device (not shown) is attached to the eye-terminal 29 or 30 of the strand 27 or 28 and the escapee gets into the device and slips therewith out the window.

Operatively it will be noted that the apparatus has three cooperative brake systems for controlling the rate of descent of the descending person or object.

First, a pair of radial disk brakes which, as described, hold the reel 17 clutched to prevent unreeling thereof under a specific minimum load or weight, but when the specific load is exceeded the hold of the clutch gives way. Disposed in the brake-drum 36a is a numerical scale to designate the points to which the nut 43 may be screwably adjusted upon the stub-shaft support 13 to create a braking contact between the end-flange 19 and the plate 9, and between the end-flange 20 and the disk 37. The nut 43 bearing against the coil spring 42 forces the brake disk 37 against the brake end-flange 20 and it also forces the brake end-flange 19 against the brake plate 9.

Second, a narrow duplex-reel 17 which, as described, contributes to the deceleration of the acceleration of the descending person or object because as the strand 27 or 28 is unwound the resistance to unwinding increases under a constant load, thereby nullifying the acceleration.

Third, two pairs of governor-brake assemblages which as already partially described, alternate in braking or governing as the reel 17 alternates in rotating clockwise or counterclockwise. Each assemblage includes a pair of governor-brake levers as 44 and 45 cooperating with a brake-drum as 36 whereby the rate of descent of the descending person or object is governed. The governor-brake levers thereof are intermediately pivoted to the reel 17 in tandem arrangement, two corresponding end-portions serving as centrifugal governor actuated by the rotation of the reel 17 centripetally levering the other or brake end-portions thereof which are provided with brake-shoes adapted to engage frictionally the brake-drum 36.

It is to be understood that the form of my in-

vention, herewith shown and described, is to be taken as a preferred example of the same, and that various changes in shape, size and arrangement of parts and the details thereof may be resorted to without departing from the spirit of my invention, or the scope of the subjoined claims.

As my invention, I claim:

1. In a device of the character described, a bracket frame including a vertical wall base-plate, which has a radial brake-face, and a stub-shaft support perpendicularly connected to the radial brake-face of said wall base-plate, said stub-shaft support including a journal-portion and a free end-portion extended from said journal-portion, said free end-portion being of a shape adapted to cooperate slidably, but not rotatably, with the hub of an element and having an end-portion thereof also screw-threaded and provided with a nut, which is adjustable on said screw-threaded end-portion; a relatively narrow radially coextensive duplex-reel rotatably mounted upon the journal-portion of the stub-shaft support, said duplex-reel including a duplex drum-hub having an inner end-flange, which has a radial brake-face, cooperating with the radial brake-face of the wall base-plate; an outer end-flange, which has a radial brake-face and is provided with a pair of diametrically opposite pivots secured to the outer end-flange externally of the radius of the brake-face of said outer end-flange; and means affording a radial partition between the end-flanges; a pair of strand elements, each connected to each drum-hub and wound in opposite direction principally upon itself to cumulate radially, thereby effecting an inherent deceleration of the acceleration of bodies being alternately descended by the respective strand elements which have the free ends thereof provided with anchor means; a radial brake means and brake-drum means slidably, but not rotatably, mounted upon the free end-portion of the stub-shaft support, said radial brake means having a radial brake-face cooperating with the radial brake-face of the outer end-flange; a compression means crowdingly communicating with the radial brake means and the adjustable nut; an opposed pair of operatively alternating governor-brake lever assemblies mounted upon the pivots and adapted to cooperate with the respective brake-drum means; and tensionally adjustable separate spring means for retracting the governor-end-portions of the lever assemblies toward the brake-drum means.

2. The device as defined in claim 1, in which the duplex reel is provided with a hood extending midway down along the periphery of said duplex-reel and having the free ends thereof flaring from the reel to facilitate the reeling thereunder of the anchor means of the strand element that idles during the lowering by the other strand element, of the first fire escapee, said anchor means striking the flared end of the hood, thereby alarming occupants in adjacent rooms.

3. In a device of the character described, a bracket-frame including a vertical wall base-plate, which has a radial brake-face, and a stub-shaft support perpendicularly connected to the radial brake-face of said wall base-plate, said stub-shaft support including a journal-portion and a free end-portion extended from said journal-portion, said free end-portion being of a shape adapted to cooperate slidably, but not rotatably, with the hub of an element and having an end-portion thereof also screw-threaded and provided with a nut, which is adjustable on said screw-threaded end-portion; a duplex-reel ro-

tatably mounted upon the journal-portion of the stub-shaft support, said duplex-reel including a duplex drum-hub having an inner end-flange, which has a radial brake-face cooperating with the radial brake-face of the vertical base-plate; an outer end-flange, which has a radial brake-face and a pair of diametrically opposite pivots secured to the outer end-flange externally of the brake-face of said outer end-flange; and means affording a radial partition between said end-flanges; a pair of strand elements, each connected to each drum-hub and wound in opposite direction and provided with anchor means on the free end thereof; a combined radial brake disk and a brake-drum member slidably, but not rotatably, mounted upon the free end-portion of the stub-shaft support, said radial brake disk having a radial brake-face cooperating with the radial brake-face of the outer end-flange; a brake-drum slidably, but not rotatably, mounted upon said free end-portion of the stub-shaft support, adjacent the combined radial brake disk and brake-drum member; a compression means crowdingly communicating with the radial brake disk and the adjustable nut; an opposed pair of operatively alternating governor-brake assemblies, each said assembly including a governor-brake-lever rockably fulcrumed on each of the pivots on the outer end-flange, one end-portion of each of said levers being on one side of each pivot, serving as centrifugal governor leverably actuating the short end-portion on the other side of the pivot, each shorter end-portion being provided with a brake-shoe adapted to cooperate with its respective brake-drum; and tensionally adjustable spring means for retracting each said governor end-portion of each lever toward its respective brake-drum.

4. An apparatus of the character described for lowering bodies, comprising a bracket frame and mechanism carried by said frame, said frame including a vertically disposed radial brake-plate and a stub-shaft support perpendicularly connected to the radial brake-plate, said stub-shaft support including a journal-portion and a free end-portion extended from said journal-portion, said free end-portion being of a shape adapted to cooperate slidably, but not rotatably, with the hub of an element and having an end-portion thereof also screw-threaded and provided with a nut, which is adjustable on said screw-threaded end-portion; said mechanism comprising a duplex-reel rotatably mounted upon the journal-portion of the stub-shaft support, said duplex-reel including a duplex drum-hub having an inner radial brake end-flange cooperating with the radial brake-plate, an outer radial brake end-flange provided with a pair of diametrically opposite pivots secured to the annular edge of said outer radial brake end-flange, a radial flange means affording a partition between said end-flanges, and a pair of strand elements, each connected to each drum-hub and wound in opposite direction and provided with anchor means on the free end thereof; a combined radial brake disk and brake-drum, and a combined radial disk and brake-drum spaced apart from each other, said radial brake-disk and said radial disk being combined with their respective brake-drums on corresponding edges of said brake-drums and provided with slidably, but not rotatable hubs, mounted upon the free end-portion of the stub-shaft support, said hubs extending in opposite directions and affording abutting spacers for the brake-drums and their respective disks, said ra-

dial brake-disk cooperating with the outer radial brake end-flange; a compression coil spring encircling the free end-portion of the stub-shaft support between the combined radial disk and brake-drum and the adjustable nut, and exerting therebetween a force against said radial disk and said adjustable nut, thereby effecting braking between the brake-plate and the inner radial brake end-flange and between the combined radial brake-disk and brake-drum and the outer radial brake end-flange, the intensity of said braking being regulated by pre-adjustment of the adjustable nut to release the unreeling of the duplex-reel with one of the strand elements loaded to a predetermined specific weight; an opposed pair of operatively alternating governor-brake assemblies mounted upon the pivots and adapted to cooperate with their respective brake-drums; and tensionally adjustable separate coil springs for 20 retracting each governor-brake lever assembly toward its respective brake drum and for regulating the braking intensity between said brake-drum and the governor-brake assembly to control the rate of descent of the body.

5. An apparatus of the character described, comprising in combination a bracket frame including a vertically disposed radial brake-plate and a stub-shaft support perpendicularly connected to said radial brake-plate, said stub-shaft support including a journal-portion and a free end-portion, said free end-portion being of a shape adapted to cooperate slidably, but not rotatably, with the hub of an element and having an end-portion thereof also screw-threaded and provided with a nut, which is adjustable on said screw-threaded end-portion; a mechanism carried by said bracket frame and comprising a duplex-reel rotatably mounted upon the journal-portion of the stub-shaft support, said duplex-reel including a duplex-drum-hub having an inner radial brake end-flange cooperating with the radial brake-plate; an outer radial brake end-flange provided with a pair of diametrically opposite pivots; and means affording a radial partition substantially medially between the end-flanges; a pair of strand elements connected to the drum-hubs, one wound clockwise and the other counter-clockwise and each provided with eye-anchor means on the free end thereof; a combined radial brake-disk and brake-drum, and a combined radial disk and brake-drum, each having a hub slidably, but not rotatably, mounted upon the free end-portion of the stub shaft support, said radial brake-disk cooperating with the outer radial brake end-flange; compression means associated with the free end-portion and operative upon the radial brakes, the compression being regulated by preadjustment of the adjustable nut; two opposed governor-brake lever assemblies mounted upon the pivots and adapted to cooperate alternately with their respective brake-drums to govern the speed of unreeling of the reel, when descending a body, each governor brake-lever assembly including two tandem arranged substantially semi-circularly arcuate governor-brake levers, each governor-brake lever rockably fulcrumed upon each of the pivots so that one end-portion of each lever, is nominally seven times as long as the short end-portion of each lever, and said governor-brake levers being arranged so that the short end-portion of each lever is adjacent to the long end-portion of the other lever and so that the long end-portions and short end-portions of one governor-brake lever assembly are disposed 60 to oppose those of the other governor-brake lever

40

45

50

55

60

65

75

assembly, thereby effecting a braking function of one of the governor-brake lever assemblies irrespective of in which direction the duplex-reel is reeled, each long end-portion having anchor means adjacent the fulcrum thereof and being arcuately and weightily adapted to serve as centrifugal governor leverably actuating the short brake end-portion thereof, each of which is articulately provided with substantially semi-circularly arcuate brake-shoe adapted to cooperate with its respective brake-drum; a pair of connecting sleeve-links, each having a pair of diametrically opposite anchor means, one sleeve link rotatably encircling the hub of the outer brake-drum between the brake-drums, and the other sleeve-link rotatably encircling the screw-threaded end-portion of the free end-portion of the stub-shaft support; and two pairs of adjustable retraction coil springs each pair connected to the anchor means of each connecting sleeve-link and to the anchor means of the long end-portion of its respective pair of governor-brake levers.

6. The device defined in claim 5 in which, the governor-brake levers have the short end-portion provided with brake-shoes inarticulately connected thereto.

7. A device of the character described comprising a frame; a shaft-support horizontally carried by said frame; a duplex-reel mounted upon the shaft-support, said duplex-reel rotating alternately upon said shaft-support and including a duplex drum-hub provided with a partition means and end-flanges, one of which has a radial brake-face, and a pair of strands opposingly wound upon said duplex drum-hub; a member having a radial brake-face, slidably, but not rotatably associated with the shaft-support, the radial brake-face of said member brakingly cooperating with the radial brake-face of said one end-flange and thereby affording a radial brake; a pair of pivots affixed to the periphery of one of the end-flanges, said pivots being horizontally disposed diametrically opposite each other; twin brake-drums slidably, but not rotatably, mounted upon the shaft-support, one of said twin brake-drums having a radial brake disk cooperating with the brake face of one of the end-flanges; tensionally adjustable compression means associated with the shaft-support and operative upon said radial brake; two opposed pairs of governor-brake levers, each pair of said governor-brake levers being rockably fulcrumed adjacent each other upon said pivots in a manner so that one end-portion of each lever is longer than the other end-portion thereof, said longer end-portion serving as centrifugal governors, and said shorter end-portion, each provided with a brake-shoe, being adapted brakingly to cooperate with its respective brake-drum, serving as brake end-portion; and two sets of tensionally adjustable spring means, each set operative upon the governor end-portion of each pair of governor-brake levers for retracting said governor end-portion of each pair of governor-brake levers toward the brake-drum when idling, and for regulating, by tensional preadjustment of said spring means, the braking intensity of the brake end-portion of each pair of governor-brake levers, when braking.

8. An apparatus for lowering bodies from elevated positions comprising a vertically disposed base-plate having a radial brake-face provided with a stub-shaft support extending perpendicularly to the plane of said radial brake-face; a

duplex-reel rotatably mounted upon said stub-shaft support, and including a duplex drum-hub, inner and outer end-flanges and a flange-like partition between said end-flanges all connected to the drum-hub, the outer sides of said end-flanges having radial brake-faces, the brake-face of the inner end-flange being in braking engagement with the radial brake-face of said base-plate, constituting a radial brake and clutch; a strand connected to and wound upon one of said drum-hubs in a clockwise direction, and another strand connected to and wound upon the other drum-hub in counter-clockwise direction, said strands having eye terminal anchor means; a pair of adjacent brake-drums slidably, but not rotatably, mounted upon the stub-shaft support for governing the rate of unreeling of the duplex-reel, one of said drums having a radial brake-face in braking engagement with the radial brake-face of the outer end-flange and constituting another radial brake and clutch coactively cooperating with the companion radial brake and clutch; tensionally adjustable spring means simultaneously operative upon said pair of radial brakes and clutches, said spring means being pre-adjusted to such a degree of tension so as to cause each radial brake and clutch to prevent the duplex-reel from unreeling with any weight under a predetermined specific weight loaded onto one of the strands and to serve as a brake when the duplex-reel is unreeling with one of the strands loaded with a weight exceeding the specific weight; a pair of pivots affixed, diametrically opposite each other, to the periphery of the outer end-flange, outside the radial brake-face, and extending out horizontally and parallelly over the brake peripheries of the brake-drums; two opposed pairs of governor-brake levers rockably and adjacently fulcrumed upon said pivots in a manner so that one pair of governor-brake levers idles with its respective idling strand, and the other pair of governor-brake levers governs and brakes while its respective strand, loaded with a weighted object, unreels; each governor-brake lever including a centrifugal governor end-portion on one side of the pivot, and a brake end-portion on the other side of the pivot, said brake end-portion being provided with a brake-shoe having an arced brake-face adapted brakingly to cooperate with the brake periphery of its respective brake-drum, and said centrifugal governor end-portion being provided with tensionally adjustable spring means for retracting said governor end-portion toward its respective brake-drum when idling, and for governing and braking when in operation during the descent of a body.

9. An apparatus for lowering bodies from elevated positions comprising: support means secured adjacent the position from which the weighted objects are to be lowered; a horizontally disposed shaft support carried by said support means; a duplex-reel rotatably mounted upon said shaft support, the outer sides of the ends of said duplex-reel having radial brake-faces; a strand connected to and wound upon one section of said duplex-reel in a clockwise direction, and another strand connected to the other section of said duplex-reel and wound in a counterclockwise direction; separate radial brake means, each having a radial brake-face, slidably but not rotatably, associated with the shaft support, each of said brake means brakingly cooperating with the brake faces of the ends of the duplex-reel and constituting radial brakes; tensionally adjustable spring

means crowdingly operative upon the radial brakes, said spring means being adjustable to such a degree of tension so as to cause the radial brakes to hold clutched, up to a predetermined specific weight loaded on one of the strands; a pair of brake-drums slidably, but not rotatably, mounted upon the shaft support; a plurality of pivots affixed to the periphery of the duplex-reel and extending out horizontally and parallelly over the peripheries of the brake drums; two opposed pairs of governor-brake levers leverably mounted upon said pivots in a manner so that one pair idles with its respective idling strand and the other pair governs and brakes while its respective strand, loaded with a body, unreels; each governor 15 brake lever of each pair of governor-brake levers including a centrifugal governor end-portion on one side of the pivot and a brake end-portion on the other side of said pivot, said brake end-

portion including a brake-shoe having an arced brake-face adapted brakingly to cooperate with the brake periphery of its respective brake-drum, and said each centrifugal governor end-portion being provided with tensionally adjustable spring means for retracting each centrifugal governor end-portion toward its respective brake-drum when said governor end-portion is idling and for controlling the braking intensity of the brake end-portion, when said brake end-portion is braking.

EDWARD SOKOLIK.
